EBENEZER MATHERS, OF ELDERSVILLE, PENNSYLVANIA.

Letters Patent No. 64,991, dated May 21, 1867.

SHEEP-SHEARS.

The Schedule referred to in these Letters Patent and making part of the same.

TO ALL WHOM IT MAY CONCERN:

Be it known that I, EBENEZER MATHERS, of Eldersville, in the county of Washington, and State of Pennsylvania, have invented a new and useful improvement in Sheep-Shears; and I do hereby declare the following to be a full, clear, and exact description thereof, reference being had to the accompanying drawing, making a part of this specification, in which—

Figure 1 is a plane or upper face view of a pair of my improved shears when open.

Figure 2 is a similar view of the same when partly closed.

Figure 3 is a lower face view of the upper set of blades and the plates to which they are attached; and

Figure 4 shows a vertical section formed by a plane passing longitudinally through one of the lower set of blades.

Like letters of reference indicate like parts.

The nature of my invention consists in the construction of sheep shears with two or more pairs of cutting blades, which blades are removable at pleasure in connection with certain other devices by which the efficiency and practical value of such shears are greatly increased.

To enable others skilled in the art to make and use my invention, I will proceed to describe its construction and mode of operation.

From wrought, rolled, or malleable iron I make the shanks or handles $a a'$, and connect them together at the rear end, either in the usual way or more commonly by a spiral spring, b , rigidly attached thereto. The other ends of the shanks $a a'$ terminate respectively in the plates $c c'$. The thickness of both the plates $c c'$ is lessened toward the head of each and at any desirable point, or they are properly shouldered so as to leave room between them for attaching and operating steel blades $d d'$, each with cutting edges or sides and each terminating in a point. Such blades I attach by screws $e e'$. Under each of the blades $d d'$ the plate c extends with a tooth-shaped projection, i , fig. 4, corresponding nearly or exactly in shape to the tooth or blade d that covers it. Such projections, i , perform the functions of guards or guard teeth to keep the blades d with their counterparts d' from cutting the skin of the sheep. The cutting blades $d d'$ of one plate c correspond in shape, size, number, and arrangement to the cutting blades d' of the other plate c' , so far that the two sets of blades $d d'$ will in pairs cut across or against each other as the shanks or handles $a a'$ are operated in the usual way. In one of the plates, and usually the upper one c' , is a slot, f , through which the headed set-screw h passes to and is screwed into the lower plate c . By tightening or loosening this screw h I cause the blades $d d'$ to work tightly to each other, or otherwise at pleasure. The slot f should of course be sufficiently large to admit of the operation of the shears in the usual way. Each set of blades $d d'$ may be made, as shown in the drawings, of a single piece of steel, or each blade may be separate and attached, as described. By loosening the screws $e e'$, I remove the blades $d d'$ for the purpose of sharpening; or, if they become broken, worn out, or injured, to substitute others. The spiral or coiled spring b should be as elastic as possible, and retain only sufficient rigidity to cause the return stroke of the blades.

The advantages which I claim consist in the greater ease with which the shears can be operated, particularly when the spiral or coiled spring b takes the place of the stiff spring of the ordinary sheep shears, in the much greater rapidity with which shearing can be done, since the operator can cut over a much larger surface with each stroke or clip of the shears than with the ordinary shears and cut more rapidly; as by the use of the guard teeth i he is in no danger of cutting the skin of the sheep. The ordinary strap spring is objectionable, as, if made sufficiently strong, it is much too rigid to be easily operated. As a modification of my invention, I sometimes attach to the plates $c c'$, in the manner above stated, a single pair of blades of the ordinary form, adjust their operation by a set-screw, h , and also connect the handles by the coiled or spiral spring b . Such spring may be rigidly attached to the handles $a a'$, or loosely so that by removing the set-screw h the handles and blades can be taken apart in order that the blades may be ground, which will be easier than removing the screws $e e'$.

What I claim as my invention, and desire to secure by Letters Patent, is—

1. Making sheep shears with removable blades for cutting or clipping, whether each blade or set of blades be made in one piece or in two or more pieces, substantially in the manner and for the purposes above set forth.

2. The mode of attaching the handles a a' of a pair of sheep shears by a spiral or coiled spring b , so as to admit of their easy operation, such spring possessing sufficient rigidity to cause the return stroke of the blades, substantially as and for the purposes hereinbefore set forth.

3. Securing a more or less intimate contact between the opposite blades or sets of blades of a pair of sheep shears by a set-screw passing through a slot in one of the blades or the plate to which such blade is attached and screwing into the other, substantially as and for the purposes above described.

In testimony whereof I, the said EBENEZER MATHERS, have hereunto set my hand in presence of—

E. MATHERS.
